Attorney.

UNITED STATES PATENT OFFICE.

HENRY HAMILTON, OF INDIANAPOLIS, INDIANA.

LAWN-SPRINKLER.

No. 806,341.

Specification of Letters Patent.

Patented Dec. 5, 1905.

Application filed March 27, 1905, Serial No. 262,114.

To all whom it may concern:

Be it known that I, HENRY HAMILTON, a citizen of the United States, residing at Indianapolis, in the county of Marion and State of Indiana, have invented new and useful Improvements in Lawn-Sprinklers; and I do declare the following to be a full, clear, and exact description of the invention, reference being had to the accompanying drawings, and to the characters of reference marked thereon, which form a part of this specification.

This invention relates to sprinklers that are designed to be connected to garden-hose and left to operate on lawns; and it has reference particularly to adjustable or changeable devices whereby different forms of sprays may be produced, and it also refers to sprinklers that may be changed so that they may be adapted to be used for discharging solid streams of water, as by ordinary nozzles.

Objects of the invention are to provide hose-nozzles with sprinkling devices that may be quickly detached therefrom and to provide a variety of sprinkling devices that may be conveniently adjusted to a nozzle so that either one of various forms of sprays may be produced at will, and, further, to provide that sprays may be projected either upwardly or horizontally from a nozzle extended horizontally on the ground.

The invention consists of a sprinkler-head provided with a plurality of types of deflecting devices and attached to an arm which is adjustably and detachably connected to a nozzle; and the invention consists, further, in the novel parts and the combinations and arrangements of parts as hereinafter particularly described and claimed.

Referring to the drawings, Figure 1 is a top plan view of the complete apparatus; Fig. 2, a longitudinal sectional view thereof; Fig. 3, a transverse sectional view on the line A A in Fig. 1; Fig. 4, an end elevation of the complete apparatus; Fig. 5, a side view of the nozzle adapted to hold the sprinkling devices; Fig. 6, a perspective view of the sprinkler-head and its supporting-arm.

Similar reference characters in the drawings designate like elements or features.

In construction the various parts may be most cheaply formed of iron.

A nozzle B is provided having a bore b, the inlet end b' of which is threaded to receive a coupling x for connecting a hose y thereto, the exterior of the outlet end c being a true circle. One side of the nozzle has a boss at-

tached thereto having a bearing-face B' parallel to the axis of the nozzle, and a pivotal stud a is attached to the boss and extends from the bearing-face at right angles thereto, the 60 stud being threaded and having a thumb-nut a' and a washer 7 thereon.

The supporting-arm C of the sprinkler devices has an oblong aperture d in one end thereof adapted to receive the stud a and is 65 clamped to the bearing B' by the nut a'. At the opposite end of the arm the sprinkler-head is attached thereto and comprises an elbow D, having a face 8 presented toward the arm C, and from the face extends a curved 70 channel e, adapted to receive the end c of the nozzle and having a restricted outlet-orifice e', at either side of which at suitable distances therefrom extend pillars f f', that are attached to the elbow D, a narrow bridge g being attached to the pillars and supporting a cone E, having its apex close to the orifice e' of the channel e. The sprinkler-head also comprises a convex deflector F, attached to one side of the elbow D, and a concave deflector G, attached to the opposite side of the elbow. 75

The nozzle is provided with a base H, having feet h and h', and is interposed between the arm C and the washer 7 on the stud a and is clamped fast by the nut a'. The washer 7 80 may of course be dispensed with, if desired.

In practical use the nozzle will be supported horizontally by the base H and the hose to which the nozzle may be connected, the feet of the base resting on the ground, and the nozzle may be drawn toward the person if one pulls the hose toward himself. If the end c of the nozzle be entered in the channel e, the spray will be thrown upwardly and spread out in all directions radially by means of the deflecting-cone E. If it be desired to produce different forms of sprays, the nut a' may be slackened, and the nozzle may then be adjusted so as to project a stream against either one of the deflectors F or G, as may be desired, as 90 indicated by dotted lines in Fig. 1, after which the nut should be tightened. If a solid stream be desired for washing windows or scrubbing purposes, the sprinkler-head may be moved entirely out of the way of the stream from the nozzle, or the arm C may be detached from the nozzle at will. 95

Having thus described the invention, what is claimed as new is—

1. A lawn-sprinkler including a nozzle provided with a pivot at a side thereof, a supporting-arm mounted on the pivot, a supporting-

base attached to the nozzle by means of the pivot, and a sprinkler-head attached to the supporting-arm and having a curved channel therein and a plurality of different forms of deflectors at either side of the channel independently thereof, and a deflector at an end of the channel of the head.

2. A lawn-sprinkler including a sprinkling-head having a curved channel therein, a convex deflector at one side of the head, a convex deflector at the opposite side of the head, a conical deflector at an end of the channel, an arm attached to the sprinkler-head, and a nozzle pivoted at a side thereof to the arm and having its outlet end movable to either the channel or the concave or convex deflectors.

3. In a lawn - sprinkler, the combination with a nozzle, of a sprinkler-head having a channel therein, pillars attached to the head, a bridge attached to the pillars, a cone attached to the pillars opposite the outlet-orifice

of the channel, unlike deflectors at opposite sides of the head, and a supporting-arm attached to the head and connected movably and detachably to the nozzle.

25

4. In a lawn - sprinkler, the combination with a nozzle, of a pivotal stud attached thereto, a supporting-arm and also a supporting-base mounted on the stud, a binding-nut on the stud, a sprinkler-head attached to the supporting-arm and thereby supported movably adjacent to the outlet-orifice of the nozzle and provided with a convex deflector and a concave deflector and also a channel between the deflectors, and a deflector supported at the outlet-orifice of the channel.

30

In testimony whereof I affix my signature in presence of two witnesses.

HENRY HAMILTON.
